UNITED STATES PATENT OFFICE.

ROBERT C. BLACK, OF DUNNELLON, FLORIDA.

DESIGN FOR AN AUTOMOBILE-RADIATOR ORNAMENT.

54,369.

Specification for Design.

Patented Feb. 10, 1920.

Application filed October 2, 1919. Serial No. 328,068. Term of patent 14 years.

To all whom it may concern:

Be it known that I, ROBERT C. BLACK, a citizen of the United States, residing in Dunnellon, county of Marion, and State of Florida, have invented a new, original, and ornamental Design for an Automobile-Radiator Ornament, of which the following is a specification, reference being had to the accompanying drawing, forming a part thereof.

Figure 1 is a front elevational view, and Fig. 2 is a side elevational view of the same, showing my new design.

I claim:—

The ornamental design for an automobile radiator ornament as shown.

ROBERT C. BLACK, M. D.
